UNITED STATES PATENT OFFICE

2,505,750

PORTABLE LADDER

Ernest Boggs, Lexington, Ky.

Application May 3, 1946, Serial No. 666,941

1 Claim. (Cl. 280—44)

(Granted under the act of March 3, 1883, as
amended April 30, 1928; 370 O. G. 757)

1

The invention described herein may be manufactured and used by or for the Government for governmental purposes, without the payment to me of any royalty thereon.

The invention to be hereinafter described relates to portable ladders.

The main objects of the present invention are to overcome and eliminate or greatly minimize objections and disadvantages of wheel-mounted ladders and especially to provide a simple, compact, efficient, safe and reliable means applicable to the stepladder type of ladders making them readily portable or transportable from one place to another and rendering them thoroughly safe against dangerous accidental skidding, slipping or like displacements.

An important aim of the invention is to present a portable caster-mounted ladder of novel construction for "grounding" the structure by elevating the casters, and which may be economically constructed by the average carpenter from stock lumber and hinges.

In order to more clearly disclose the construction, operation and use of the invention reference should be had to the accompanying drawings forming part of the present application.

In the drawings:

Fig. 1 is a side elevation, partly broken away, of a ladder with the invention applied and in operative or travel position;

Fig. 2 is a like view with the invention in inoperative or grounded position;

Fig. 3 is a bottom plan view of Fig. 1; and

Fig. 4 is a top plan view of Fig. 1, the ladder being cut off at a point directly above the base frame, the upper framework of the ladder itself being omitted.

Fig. 5 is an enlarged detail of a hinge between the toggle and ladder base.

There is shown a ladder or stair 1, which, with a conventional truss frame work, is supported on a horizontal rectangular base A, consisting principally of two parallel side stringers 15 and two cross beams 16 at the under side set edgewise against the stringers. The latter constitute foot pieces for the base, to rest upon the ground at times. To this base are hinged two triangular frames 2, by ordinary plate hinges 3 at their bases, as, for instance, in Fig. 5, or any other suitable means permitting the frames to be swung upwardly from such connections. Preferably, these frames are flexibly connected at their adjacent angles in such manner that they may move from a flat, lowered or operative position to a flexed, tipped or angular position. A simple plate hinge

4 is very practical, and, in effect, makes a toggle lever unit of the two frames. Each of these frames carries on its underside, at the two corners thereof nearest the hinges 3, swivelled castors 5. The parts are so proportioned and assembled that when the frames 2 are swung down into the same plane, the supporting rollers of the castors 5 will be forced appreciably below the plane of the ladder feet 16 thereby lifting the ladder from its feet and transferring its weight to the castors on the frame A and making it portable. To spread the toggle and transfer the ladder weight to the castors a hand lever 6 is provided. Lever 6 has one end pivoted at 7 to the rear truss framework of the ladder. At about its center it is connected pivotally to a bar 8 which extends downward from the lever toward base A. The lower end of the bar 8 is hinged at 9 to a cross bar 10 over the base A which extends across the latter to the far or left side, where it is hinged or otherwise suitably connected at 11 to the side member 15 of frame A. It will be noticed that bar 10 extends across the ladder a short distance above the hinge 4 at the center of the toggle formed by the frames 2. At that point a short presser block or the like 12 is set between bar 10 and the inner angle of one member of the toggle. By depressing lever 6 the ladder may be transferred from its feet to the castors and made portable. By swinging the end of the lever 6 beneath the stop block 13 on the side of a newel 17 beside the ladder, the castors may be indefinitely kept this way. As soon as the lever is disengaged from block 13 and relieved of manual pressure, the weight of the ladder will, of course, force the frames 2 up so that castors 5, though in light engagement with the supporting surface, will be ineffective as supports, as may be seen in Fig. 2.

By providing swivel mounting of the castors the ladder may be turned about, steered and guided in any direction desired toward, along or between stacks and storage piles without difficulty.

As will be readily seen on reference to the drawings, the lever 6 is within easy reach of anyone standing on the ground by the ladder.

Many changes may be made in the construction, arrangement and disposition of the various parts of the invention within the scope of the appended claims without departing from the invention, and it is meant to include all such within this application wherein only one preferred form has been illustrated, purely by way of example and with no thought or intention to, in any degree, limit the invention thereby.

Having thus described my invention, what I claim and desire to protect by Letters Patent is:

In a ladder truck, a base frame having ground engaging feet to support the same, two planiform lever frames having base edges extending the width of the base frame pivoted at opposite ends of the base frame and pivotally connected mutually to form a toggle unit, a cross lever pivoted on one side of the base frame, a presser member intermediately of the cross lever between the cross lever and at least one toggle member, a hand lever of the second order pivoted at the side of the frame adjacent the free end of the cross lever, a pressure bar pivotally connected between the hand lever and said end of the cross lever, a stop on the truck frame arranged to receive the swinging end of the hand lever thereunder when operated to depress the toggle, and castors on the under sides of the toggle lever

frames positioned to be moved downwardly with the toggle lever frames to a truck-supporting position below the level of said ground engaging feet when said hand lever is engaged under said stop.
